UNITED STATES PATENT OFFICE.

OTTO J. GROEHN AND FREDERICK L. ALLDIS, OF DETROIT, MICHIGAN, ASSIGNEES TO
BRISCOE MANUFACTURING COMPANY, OF DETROIT, MICHIGAN, A CORPORATION
OF MICHIGAN.

RADIATOR.

1,396,931.

Specification of Letters Patent. Patented Nov. 15, 1921.

Application filed April 5, 1915. Serial No. 19,355.

To all whom it may concern:

Be it known that we, OTTO J. GROEHN and FREDERICK L. ALLDIS, citizens of the United States of America, residing at Detroit, in the county of Wayne and State of Michigan, have invented certain new and useful Improvements in Radiators, of which the following is a specification, reference being had therein to the accompanying drawings.

10 The invention relates to radiators, and more particularly to radiators for engines of motor vehicles or the like.

The invention has among the objects thereof to produce a simple and efficient 15 construction of radiator in which the water passages are separated from each other by more than a single row of air tubes; to provide such a type of radiator which may be easily and cheaply manufactured. Further, 20 to provide such a type of radiator in which the amount of material required for making up the radiator sections is materially reduced over constructions now in use.

Other objects of the invention will more 25 fully hereinafter appear.

The invention resides in the peculiar construction, arrangement and combination of parts as hereinafter set forth and particularly pointed out in the claims.

30 In the drawings,—

Figure 1 is an enlarged fragmentary vertical sectional view;

Fig. 2 is an enlarged perspective view showing the manner of assembling a unit;

35 Fig. 3 is a top plan view illustrating the relation of certain parts;

Fig. 4 is a cross sectional view on the line $\alpha-\alpha$ of Fig. 1; and Fig. 5 is an enlarged perspective view showing the manner of assembling a unit.

In the drawings, the cross-section of the radiator cells is shown hexagonal, but the invention is equally adapted for use with cells of other cross-sections.

40 Referring to the one embodiment of the invention shown in the drawings, the radiator A is composed of a plurality of units B. The sides of adjacent units form the sides of the water passages A' and the units are so constructed that the sides of adjacent water

passages are separated by a plurality of rows of cells. Thus each of these units comprises plates C and D and an intermediate plate or fin E. The fin E is shaped to form cell portions with the portions for adjacent cells facing in opposite directions. In the particular structure shown, each of such cell portions forms one-half of a hexagon. The plate C is similarly formed and when the plates C and E are assembled in operative 60 relation as shown in Fig. 1, there is formed a vertical row of hexagonal cells F. In order to provide a second row of hexagonal cells between the plates C and D, the plate D which is of the same general configuration 65 as the plates C and E, has a series of strips G struck out therefrom immediately adjacent its forward and its rear edges. The strips G are shaped to form three sides of a hexagon and coöperate with the outwardly 70 bent portions H of the plate D to provide another vertical row I of hexagonal cells at the front and back of the radiator. When the plates C D and E are assembled the corresponding cells of the rows F and I are in 75 horizontal alinement. This gives a third vertical row J of hexagonal cells, the members of which are alternated with the members of the rows F and I.

The plates C and D are preferably formed 80 of a single strip of metal bent upon itself to form the closed end K, while the free ends of the strip are seamed together as at L. When the units are assembled the front and rear faces of the radiator are dipped in 85 solder in the usual manner. The ends M of the plate E engage the opposite ends N of the plates C and D and are soldered thereto when the radiator is dipped. As the solder seals the joints between the various interengaging portions of the plates, the front of the radiator has the same appearance as it would have if the rows of cells I and J were complete tubes extending from front to back 90 of the radiator.

95 The forward and rearward edges of the plates C and D are embossed as indicated at O, and when adjacent sections are assembled the embossed portion acts to space the sections, forming water spaces A' therebetween 100.

in the well-known manner, the strips G being so arranged that the embossed portion is not entirely cut off.

To assist in positioning the member C in relation to the member E during the assembling of the parts, there is struck out from the member E a plurality of strips or positioning sections a which are shaped to fit nose portions of the plate C that form halves of the cells F. Similarly in order to position the plate D in relation to the plate E, the latter is provided with a plurality of strips or positioning sections b which are struck out from the plate E and extend in the opposite direction from the strips a. The strips b are shaped to fit within the space between the adjacent portions G of the plate D. Since the positioning strips b bear against the plate D at a plurality of points, they not only act as positioning means, but also serve to strengthen the connection between the plates D and E.

As shown in Fig. 4 the strips b are formed adjacent the front and rear edges of the plate E in an overlapping relation to the strips G, whereby the strips b and G reinforce each other as shown at e.

The back face of the radiator is formed in the same manner as described in connection with the front face, and while there is shown in the drawings but two series of positioning sections a, it will be readily understood that as large a number of such positioning strips as is desired may be employed. Similarly there may be struck out from the member E as many of the positioning and strengthening strips b as is desired.

While a very desirable form of the invention is shown in the drawings, we do not desire to limit the protection to the particular structure illustrated.

What we claim as our invention is:

1. In a radiator, a section composed of a plate shaped to form some of the sides of a row of cells, said plate having struck-out portions adjacent its forward edge shaped to complete the sides of said row of cells, a second plate also shaped to form some of the sides of a row of cells, and a third plate arranged intermediate said plates shaped to form with the second mentioned plate the sides of a second row of cells.

2. In a radiator, a section composed of a plate shaped to form some of the sides of a row of cells, said plate having struck-out portions adjacent its forward edge shaped to complete the sides of said row of cells, a second plate also shaped to form some of the sides of a row of cells, a third plate arranged intermediate said plates shaped to form with the second mentioned plate the sides of a second row of cells, and positioning strips struck out from one of said plates for engaging another of said plates.

3. In a radiator, a section composed of a

plate shaped to form some of the sides of a row of cells, said plate having struck-out portions adjacent its forward edge shaped to complete the sides of said row of cells, a second plate also shaped to form some of the sides of a row of cells, a third plate arranged intermediate said plates shaped to form with the second mentioned plate the sides of a second row of cells, and positioning strips struck out from opposite sides of the third plate for engaging the other plates.

4. In a radiator, a section composed of a plate shaped to form portions of a plurality of cells, said portions alternating with channel forming portions, said plate having struck-out portions adjacent its forward edge shaped to complete said cells, a second plate shaped to form portions of a plurality of cells, said portions alternating with channel forming portions, a third plate of configuration similar to the second plate and co-operating therewith to complete alternate cell portions of the second plate and shaped to form with the struck-out portions of the first plate a row of cells.

5. In a radiator, a section composed of a plate shaped to form portions of a plurality of cells, said portions alternating with channel forming portions, said plate having struck-out portions on the inner face thereof and adjacent its forward edge shaped to complete said cells, a second plate shaped to form portions of a plurality of cells alternating with channel forming portions, a third plate of configuration similar to the second plate and co-operating therewith to complete alternate cell portions of the second plate and shaped to form with the struck-out portions of the first plate a row of cells, and positioning means upon the intermediate plate for engaging the first and second plates.

6. In a radiator, two parallel plates respectively having alternated inwardly and outwardly bent portions, of strips struck out from the outwardly bent portions of each plate in a complementary relation thereto, and engaging the inwardly bent portions of the other plate, the strips struck out from the respective plates being overlapped.

7. A radiator section, comprising three corrugated plates, forming three rows of similar polygonal cells, the cells of one of said rows forming horizontally adjacent pairs with those of another, and the cells of the third row being alternated with said pairs.

8. A radiator section comprising three corrugated plates, one intermediate the other two, coacting to form three rows of hexagonal cells, the intermediate plate having struck out portions engaging each of the other two plates to relatively position the three plates.

9. A radiator section, comprising three

corrugated plates, one of which is intermediate the other two, said plates coacting to form two outer rows of hexagonal cells, the cells of one of which adjoin those of the other, and a third row of hexagonal cells, which are spaced apart by the adjoining cells of the other two rows.

In testimony whereof we affix our signatures in presence of two witnesses.

OTTO J. GROEHN.

FREDERICK L. ALLDIS.
